ATTORNEYS

UNITED STATES PATENT OFFICE.

JOHN WARREN WATSON, OF WAYNE, PENNSYLVANIA.

GLOVE.

Application filed March 13, 1918. Serial No. 222,266.

To all whom it may concern:

Be it known that I, JOHN W. WATSON, a citizen of the United States, and a resident of Wayne, in the county of Delaware and

5 State of Pennsylvania, have invented a certain new and useful Glove, of which the following is a specification.

This invention relates to a glove of novel form for the purpose of keeping the hand 10 warm when in its natural bent and working position. This is accomplished by providing a covering for the hand to retain heat, and by so forming the glove as to not interfere with heat supply i. e. circulation of blood 15 in the hand and fingers when the same are in their natural bent and working position.

The common practice in gloves and mittens intended to keep the hands warm is to construct and form them so that they normally 20 lie flat. To grasp anything, therefore, such as an automobile wheel, a hammer handle or any other object designed to be grasped by the hand, requires that the hand and fingers must force the glove out of its normal 25 flat form and into a curved position. This forcing of the glove into this curved position causes pressure against the finger tips which immediately stops or reduces blood circulation. With circulation thus stopped or 30 reduced, the fingers soon become numb and cold and this numbness and cold further stops blood circulation until the entire hand becomes cold. The hand thus becomes cold in spite of the heat retaining qualities of 35 the glove material or glove lining.

It has been found, in automobile mitts, as customarily constructed for the purpose of keeping the hands warm, that the hand soon becomes very cold while forcing the mitt into 40 a curved position to conform to the curved section of the steering wheel, but quickly warms up again if the hand is unbent from the steering wheel and straightened out to conform to the normal or flat form of the mitt. The reason for the hand being cold in 45 one position and warm in the other position is simply because of stoppage of blood circulation in the one case and freedom of blood circulation in the other.

50 It is the purpose of this invention to provide a glove adapted for the purpose of keeping the hand warm when in its natural bent and working position by minimizing the pressure against the finger tips or against 55 any other part of the hand and thus per-

mitting free circulation of the blood while the hand is being held in its natural curved and working position.

As is made clear by the accompanying drawings, my invention relates to a glove so formed that, in its normal position, it is already curved and hence requires no pressure from the hand to curve it around the object to be grasped. In a glove thus normally formed, the blood is permitted to maintain its free circulation and thus impart its warmth to the hand while the hand is bent and grasping its object.

Various means may be utilized in constructing a heat-retaining glove so that the same normally assumes such a position as not to require pressure from the hand and fingers to bend or maintain the same in a bent or working position. One efficient construction for this purpose is shown and described herein merely by way of example, it being understood that the invention is not limited to the particular embodiment illustrated as it will be apparent that many modifications thereto may readily be made without departing from the spirit and scope of my invention.

Referring to the drawings, Fig. 1 is a cross sectional view of my novel form of glove showing the same normally conforming to the natural curved and gripping position of the hand. Fig. 2 is an elevation of the glove removed from the hand where it will be noted that the glove, unaided by the hand, maintains this bent and working position.

One type of glove illustrated herein, which is adapted to normally assume, unaided, a position which will not interfere with proper blood circulation while the hand is in its natural working position, comprises a construction wherein the proportioning of the palm section (1) relative to the back section (2) tends to normally hold the glove in the desired curved position. The palm section herein is made shorter than the back section. It is obvious, however, that this same normal curvature of the glove could be secured in many other ways, such as, for example, by merely pre-forming the glove into a curved position.

Moreover, it is evident that the glove or mitt, although held together by a seam or seams, need not be made of the number of pieces disclosed in order to be so shaped as to cause the completed glove to normally

assume this curved position and thus minimize the tendency to interfere with the circulation of the blood in the hand when the same is held in its bent or working position.

5 If desired, the thumb piece (3) may also be made to assume, unaided, some such curved position as that shown in the present embodiment.

It is understood that the novel form of 10 glove or mitt illustrated herein is to be provided with a lining of suitable warmth-retaining material or materials or is to be constructed throughout of material or materials which are suitable for retaining heat.

15 Having thus described my invention, I

claim and desire to protect by Letters Patent of the United States:

1. The combination of a covering for the hand preformed to conform with the natural bent and working position of the hand; and 20 a heat retaining lining within said covering.

2. A covering for the hand, preformed to conform to the natural bent and working position of the hand, said covering on the inside being provided with warmth retaining material of substantially uniform thickness throughout. 25

In witness whereof, I have hereunto set my hand this 12th day of March, A. D., 1918.

JOHN WARREN WATSON.
